UNITED STATES PATENT OFFICE.

ROBERT L. MCINTYRE, OF TORONTO, ONTARIO, CANADA.

STRUCTURAL-STEEL FABRICATION.

Application filed August 2, 1926. Serial No. 126,676.

The principal objects of the invention are to enable the use of very light sections of structural steel in the arrangements of the floor supports between beams in buildings, 5 to effect a material reduction in the cost of such structures and to provide a structure which will greatly enhance the strength of the entire fabrication.

The principal feature of the invention consists in rigidly securing a stirrup member 10 to the end of a beam section to rest upon the flange of an adjoining beam section and to form a rigid beam support.

In the drawings, Figure 1 is a perspective view of a main beam of a building structure showing a pair of "joist" beams supported therefrom by my improved construction;

Figure 2 is a sectional elevation showing 20 the application of the present invention.

It is desirable in present day building construction to provide floor supports or "joists" in the form of light rolled I sections and such joists have been supported in loose stirrup 25 structures hung on the main beams. Such construction has certain objections both as to cost and effectiveness and my present invention proposes to greatly simplify the structure and to enhance its strength.

The joist beams 1 have secured to their 30 ends a strip of metal, preferably formed from a flat steel bar of a suitable thickness, into the Z-shaped stirrup members 2. The lower right angularly bent end 3 extends under the bottom flange 4 of the beam 1 and the vertical portion abuts the squared end 35 of the beam while the right angularly turned end 5 extends outwardly and forms a bracket extension which rests upon the top of the flange 6 of the main beam 7 which, as shown in Figure 2, may be encased by concrete 7' and the joists 1 are here shown supporting 40 a floor 7" which may be of concrete.

The stirrup member 2 is rigidly connected 45 to the beam 1 at the bottom flange preferably by having the end edge of the flanged portion 3 secured to the flange 4 by welding forming the joint 3' and the end edge of the top flange 8 of the beam 1 is rigidly connected 50 to the angle of the upright 2 and flange 5 by the welded joint 9.

The joist members may be fabricated as 55 thus described in the shop and when taken to the job are simply dropped into place and properly spaced along the main beams. They may be used in this manner or the end

edges 10 of the flanges 5 may be secured to the flanges of the main beams by welding. The welding of the top flange 8 of the joist beams to the angled stirrup member 2, together with the securing of the edge of the flange 3 to the under flange 4 of the beam provides a very positive and a very strong end connection which has even greater strength than the beam section and when the stirrup member is welded to the main beam as described, an extremely valuable addition has been made to the ultimate strength of the building, as each joist will form a positive tie between the main cross beams, adding materially to wind resistance and to distribution of lateral stresses.

The advantages to be obtained from a fabrication such as described will be readily apparent to those skilled in the art. Much 75 time will be saved in the placing of the joists and immediately they are properly spaced the securing in position can be effected quite rapidly with the use of an electric or acetylene welder.

It will also be understood that the extremely simple shape of the stirrup members reduces the cost very materially and further, there is no "field" work required in the assembling or adjusting of parts other than 85 the actual spacing of the joists and the welding of same in position.

What I claim as my invention is:

1. A structural steel fabrication, comprising in combination with a beam a metal member formed of Z-shape abutting the end of the beam having one flange extending under the bottom flange of the beam and fused thereto, and the other flange extending outwardly from the beam, the abutting 95 end of the top flange of the beam being fused to the outwardly extending flange.

2. A structural steel fabrication, comprising the combination with a steel beam section, of a Z-shaped member having a web 100 portion abutting the end of the beam section and one flange extending under the beam section and fused along its edge to the lower flange of the beam section back from the end edge thereof, and a fused joint securing the end edge of the top flange of the beam section to the upper end of the Z-member and integrally uniting the two.

3. A structural steel fabrication, comprising the combination with the main beams of 110 the building, of joist beams arranged transversely between said main beams and Z-

shaped stirrups having their upper flanges arranged in alignment with the upper joint beam flanges and resting on the upper flanges of the main beams and their under flanges supporting the joists, said Z members being permanently fused at their upper flange ends to the upper flanges of the main beams and permanently fused to the joist members.

4. In a structural steel fabrication, a metal beam, and a metal stirrup member permanently secured to the end of the beam and having a rigid supporting flange fused to the beam and extending outwardly beyond the end of the beam and forming a rigid extension therebeyond. 10

ROBERT L. McINTYRE.
